UNITED STATES PATENT OFFICE.

EDWARD R. BENSON, OF MINNEAPOLIS, MINNESOTA, AND MILTON S. CRANDALL, OF SIOUX CITY, IOWA.

VEHICLE DUMP.

Application filed December 18, 1919. Serial No. 345,863.

To all whom it may concern:

Be it known that we, EDWARD R. BENSON and MILTON S. CRANDALL, citizens of the United States, and residents, respectively, 5 of Minneapolis, in the county of Hennepin and State of Minnesota, and of Sioux City, in the county of Woodbury and State of Iowa, have invented certain new and useful Improvements in Vehicle Dumps, of which 10 the following is a specification.

The invention has for its primary object the production in a vehicle dump embodying a platform and a tilting vehicle support pivoted thereon, of improved mechanism for 15 actuating and positively sustaining the support in any inclined position.

Furthermore the invention contemplates in a scales platform carrying a tilting vehicle support, improved actuating means 20 carried by the platform to actuate and positively sustain the support in any desired inclination and to in no way interfere with the free operation of the scales platform.

Still another object of the invention is the 25 production in a platform having a tilting vehicle support of improved actuating means, comparatively simple and inexpensive in construction and requiring but a minimum amount of power.

With these and other objects in view, the 30 invention consisting in the construction, combination and novel arrangement of parts, will be fully understood from the following description, reference being had to the accompanying drawings, which form a part of 35 this application and in which like characters of reference indicate corresponding parts throughout the several views, of which,—

Fig. 1 is a fragmentary vertical section of 40 a scales platform equipped with the preferred embodiment of our invention and taken approximately on the line 1—1 of Fig. 2;

Fig. 2 is a transverse section of the same taken on the line 2—2 of Fig. 1 and;

Fig. 3 is an enlarged front elevation of the 45 jack, parts being cut away.

Referring to the illustrations, the platform particularly shown includes a scales platform having a flooring, 4, supported by 50 beams, 5, the flooring is provided with an opening, 6, in which is mounted a tilting vehicle support including a flooring, 7, mounted on longitudinal beams, 8, pivoted as at 9, to the scales platform.

From the platform depend U-shaped

frames, 10, suitably secured to beams, 5, and interconnected at their lower ends by a pair of cross members, 11, between which is interposed a sleeve, 12, through which freely slides a threaded shaft, 13, the upper end of 60 which is provided with a head, 14, pivoted on a wrist pin, 15, carried by suitable bearings, 16, mounted on the under side of a cross member, 17, interconnecting the tilting beams, 8.

Positioned above the sleeve, 12, is a bevel gear, 18, having on its underside a hub, 19. The adjacent ends of the sleeve and said hub are provided with ball races, 20, between which are interposed ball bearings, 21, to insure frictionless operation of the gear. The upper face of the gear is provided with a hub, 22, threaded on the shaft, 13. The opposite sides of the gear, 18, are intermeshed with an idler bevel pinion, 23, and a drive 75 pinion, 24, said idler pinion being mounted freely on one of two trunnions, 25, on the sleeve, 12, and journaled in suitable bearings, 26, mounted on the cross members, 11. Disengagement of the gear, 18, from its companions, is prevented by means of a yoke, the web of which is formed with a collar, 27, which freely encircles the threaded shaft, 13, and the arms, 28, of which are pivoted coaxially with the trunnions, 25. The gear, 24, 80 is secured to a shaft, 29, journaled in a suitable bearing, 30, on the frame members, 11; and carrying a sprocket wheel, 31, connected by a sprocket chain, 32, with a relatively larger sprocket wheel, 33, rotatably supported by a suitable frame, 34, mounted on the platform; and adapted to be manually rotated.

It is now clear that the tilting support, mounted to swing vertically on its pivot, 9, 85 is readily raised and lowered according to the direction of rotation of the hand wheel, 33, it is also obvious, that the jack shaft will sustain the support in any inclined position.

Having thus described our invention what 100 we claim as new and desire to secure by Letters Patent of the United States, is,—

1. In a vehicle-dump, a platform, a vehicle-tilting support pivoted thereon, a supporting frame depending from the platform, 105 and including bearing supports, bearings mounted on the bearing supports, a threaded jack-shaft operable to lift the vehicle support, and disposed between the bearings, a guide sleeve on the shaft and having trun- 110

nions journaled in said bearings whereby the shaft may oscillate, a gear threaded on the shaft and resting on the sleeve, a yoke pivoted on the trunnions to prevent displacement of the gear, and means for driving the gear in either direction.

2. In a vehicle-dump, a platform, vehicle-tilting means thereon, and operating mechanism therefor comprising a supporting frame 10 including side members depending from the side portions of the frame and cross-members interconnecting the lower ends of said depending members, a threaded shaft disposed between the cross-members, a sleeve 15 freely encircling the shaft and having trunnions, bearings on the cross-members for piv-

otally supporting the trunnions, a bevel-gear threaded on the shaft and rotatably supported by the sleeve, a yoke having its arms pivoted coaxially with the trunnions, the web 20 of the yoke being positioned to prevent upward movement of the gear, a bevel-gear rotatable coaxially with the trunnions and intermeshed with said first gear, a horizontal shaft on which said second gear is fixed, and 25 means on the platform for driving said latter shaft.

In testimony whereof we have hereunto set our hands this 4th day of October, 1919.

EDWARD R. BENSON.
MILTON S. CRANDALL.
